By his Attorney
Alde Pompeville

UNITED STATES PATENT OFFICE.

GUSTAV N. HALGREN, OF BAYONNE, NEW JERSEY.

CRACK AND SAG PROOF CORNER-STRIP.

1,329,899.

Specification of Letters Patent.

Patented Feb. 3, 1920.

Application filed July 15, 1918. Serial No. 244,922.

To all whom it may concern:

Be it known that I, GUSTAV N. HALGREN, a citizen of the United States, and a resident of Bayonne, in the county of Hudson and 5 State of New Jersey, have invented certain new and useful Improvements in Crack and Sag Proof Corner-Strips, of which the following is a specification.

This invention relates to crack and sag 10 proof corner strips. Its object is the production of strips which when secured to the juncture of a pair of walls making angles with each other, will prevent cracks at said juncture in case any sagging takes place 15 of the walls. By this means wall paper or decorations on the wall adjacent to their juncture are preserved. The strips are longitudinally and slidably connected at their juncture, and thereby permit the walls 20 to sag, without injuring the appearance of the wall paper or the decorations that may be thereon.

In the accompanying drawing Figure 1 represents an elevation of a pair of strips 25 exemplifying the invention with the lath of one of the walls with which it coacts; Fig. 2 is a top plan view of the strip shown in Fig. 2, with its coacting walls; Fig. 3 is a front elevation of one of the details of the invention; Fig. 4 shows a top plan view of Fig. 3 and Fig. 5 shows a top plan view of a pair of the strips on a reduced scale secured to a pair of walls.

A strip 20 preferably of wood is shown 30 with the front face 21, the rear face 22, the beveled end 24 and the tenon 25. An accompanying strip 28, also preferably of wood is indicated with the front face 29, rear face 30, beveled end 31 and the mortise 35 40 32, which latter engages the tenon 25, to provide a longitudinal slidable joint between the strips.

On the front faces 21 and 29 of the strips there is secured the wall paper 36 in the 45 usual way, and at the jointure 38 of the strips, the paper is cut. To the rear faces 22 and 30 of the strips is secured, by means of tacks 41, a piece of fabric 42, which is 50 preferably dust and water proof and protects the joint between the strips. Clamps 55 preferably of metal join the strips on their rear faces at intervals. Each of the clamps comprises the body portion 44, with the legs 45 and 46 at right angles thereto. A 55 tapered hook end 47 is formed with the leg 45, and a tapered hook end 48 is formed

with the leg 46. The hook end 47 is made to enter the beveled end 24 of the strip 20, and the hook end 48 is made to enter the rear face 30 of the strip 28, the hook end 48 passing through the fabric 42. 60

A framing 50 of a wall has connected thereto the studs 51 and 52 and a second wall at right angles to the first one, is indicated at 53 with the studs 54 and 55. Lath 58 are nailed in the usual way to the studs 51 and 52 and lath 59 are nailed to the studs 54 and 55. Plaster 60 and 61 covers the lath in the usual manner and engages the beveled ends 24 and 31 respectively of the 70 strips 20 and 28, thereby enabling the strips to have their outer surfaces in line with the outer surfaces of the plaster.

In case the walls sag, each of the strips will move with its wall and the jointure between the accompanying ends of the wall paper 36 will not show any crack. The fabric 42 will give sufficiently and the clamps having the body portions 44 will swing on their hook ends to permit the strips 80 with their walls to move longitudinally without spreading. In place of covering the strips and walls with wall paper, they may be decorated. The invention provides means for preventing cracks at the juncture 85 of the walls, and thereby preserves the wall paper or the decorations and the like with which the walls may be decorated. 75

The invention may be modified in various ways within the meaning of the claims and 90 these modifications are intended to be included in the spirit of the claims.

Having described my invention what I 95 desire to secure by Letters Patent and claim is:—

1. For the juncture of a pair of walls with plaster the combination of a pair of strips slidably connected at a pair of accompanying edges thereof, one of the strips fastened to one of said walls and its plaster, 100 the outer face of the strip in line with the outer face of the plaster, the other strip fastened to the other wall and its plaster, and means to prevent the strips spreading and at the same time allowing them to slide one 105 relatively to the other.

2. For the corner of a pair of walls the combination of a pair of strips and plaster, the strips slidably connected at a pair of their accompanying edges, one of said strips 110 fastened to one of said walls and plaster and the other strip fastened to the other

wall and its plaster, and a clamp connecting said strips, permitting one strip to slide with respect to the other, maintaining them in operative position and preventing them 5 spreading.

3. For the juncture of a pair of walls with plaster the combination of a pair of strips, one of said strips fastened to one of said walls and plaster, the other strip fastened 10 to the other wall and plaster, one of said strips having a mortise formed therewith and the other strip having a tenon engaging said mortise and clamps each with a pair of hook ends, the said hook ends engaging said 15 strips and shaped to enable one strip to slide with respect to the other and maintaining the mortise joint of the strips in operative position.

4. The combination of a pair of walls 20 making angles with each other, plaster covering each wall, a pair of strips fastened to the walls at their juncture and embedded in the plaster, the strips making angles with each other and slidably connected at their 25 juncture, means to maintain the strips in slidable operative position and a fabric covering the rear faces of the strips to maintain their juncture dust proof, the said fabric covering said juncture in all positions of 30 the strips.

5. The combination of a pair of walls making angles with each other, plaster covering a face of each wall, a pair of strips making angles with each other and located 35 in the corner of the walls, each of said strips having a beveled side and the other sides of the strips longitudinally and slidably

locking with each other, one of said strips fastened to one wall and engaged by the plaster thereof and the other strip fastened 40 to the other wall and engaged by the plaster of the latter, means to render dust proof the juncture of the walls in different positions of the latter, wall paper covering one wall and wall paper covering the other 45 wall, the said wall paper meeting at the juncture of the strips so that one wall paper can move with its strip and wall independently of the other, a clamp with a pair of hook ends engaging said strips the hook 50 ends shaped to permit the strips to longitudinally move with respect to each other.

6. The combination of framing for a pair of walls making angles with each other, lath secured to both walls, a strip fastened to the lath of each wall, a longitudinal and slidable connection for the juncture of the walls, plaster covering the lath and embedding the outer sides of said strips, a pair of faces of the strips registering with the 60 outside faces of the plaster, means to protect dust proof the juncture of the strips in any relative position thereof and clamps engaging said strips to prevent them spreading and enabling them to longitudinally slide one with respect to the other.

Signed at Bayonne, in the county of Hudson and State of New Jersey, this 6th day of July, A. D. 1918.

GUSTAV N. HALGREN.
